BOWL

George Sakier, New York, N. Y., assignor to Fostoria Glass Company, Moundsville, W. Va., a corporation of West Virginia

Application May 11, 1948, Serial No. 146,303

Term of patent 14 years

(Cl. D36—2)

To all whom it may concern:

Be it known that I, George Sakier, a citizen of the United States of America, residing at New York city, in the county of New York and State of New York, have invented a new, original, and ornamental Design for Bowl, of which the following is a specification, reference being had to the accompanying drawing, forming a part thereof, wherein:

Fig. 1 is a top plan view of a bowl, showing my new design;

Fig. 2 is a side elevational view; and

Fig. 3 is a vertical sectional view thereof taken on the line 3—3 of Fig. 2.

I claim:

The ornamental design for a bowl, as shown.

GEORGE SAKIER.
